COMBINED COIN REPOSITORY AND CALCULATOR OR SIMILAR ARTICLE

Eugene P. Bell, 9662 Nadine, Temple City, Calif.

Filed July 1, 1964, Ser. No. 80,659

Term of patent 14 years

(Cl. D34—11)

FIG. 1.

FIG. 2.

FIG. 3.

FIGURE 1 is a perspective view illustrating the front of a combined coin repository and calculator or similar article, showing my new design;

FIGURE 2 is a perspective view illustrating the back of the combined coin repository and calculator or similar article; and

I claim:

The ornamental design for a combined coin repository and calculator or similar article, as shown.
